UNITED STATES PATENT OFFICE.

ROBERT H. DUESING, OF CHICAGO, ILLINOIS.

CARPET-RENOVATOR.

No. 850,911.

Specification of Letters Patent.

Patented April 23, 1907.

Application filed November 6, 1905. Serial No. 286,135.

To all whom it may concern.

Be it known that I, ROBERT H. DUESING, a citizen of the United States, residing at Chicago, in the county of Cook and State of Illinois, have invented certain new and useful Improvements in Carpet-Renovators; and I do declare the following to be a full, clear, and exact description of the invention, such as will enable others skilled in the art to which it appertains to make and use the same.

My invention relates to improvements in devices or mechanisms for removing dust and dirt from carpets and other covers while on a floor or other surface.

15 The object of the invention is to improve and simplify the construction and operation of devices of this character and thereby render the same more efficient.

Another object of the invention is to provide a device of this character in which two or more opposing air blasts or jets will be directed toward or across each other, so as to effectively remove dust from carpets, velvets, furs, and the like having a nap surface.

25 With the above and other objects in view my invention consists in certain novel features of construction, combination, and arrangement of parts hereinafter described and claimed.

30 In the accompanying drawings, Figure 1 is a perspective view of my improved carpet-renovator. Fig. 2 is a vertical longitudinal sectional view through the same. Fig. 3 is a vertical transverse sectional view. Fig. 4 is a horizontal sectional view taken on the line 4-4 in Fig. 2; and Fig. 5 is a perspective view of one of the air-discharge nozzles, parts being broken away to more clearly illustrate the construction.

40 Referring to the drawings by numeral, my improved dusting or renovating device, which is adapted to be moved over the surface to be cleaned, has a box or casing 2, which serves as a dust and dirt receptacle.

45 The receptacle 2, as shown, is of rectangular form having an open top, around which is formed an outwardly-projecting flange 3 and a flat bottom 4, having rounded front and rear edges 5 and a centrally-disposed longitudinally-extending opening or slot 6. Mounted in the dust box or receiver 2 above the opening 6 is a longitudinally-extending pair of air-discharge nozzles 7. These nozzles 7 are pivotally mounted in parallel relation between the ends of the box 2, so that they may

be swung or adjusted toward and from each other to direct the jets or blasts of air discharged from them at a greater or less angularity, according to the length of the nap or the character of the carpet or other surface 60 being cleaned. These nozzles are similar in construction and each preferably consists of a substantially wedge-shaped head 8, (here shown in the form of a casting,) in which is formed a cavity 9, opening upon one face of 65 the head. In this open face 10 of the discharge head or nozzle is formed a recess 11 to receive a cover-plate 12 and a sheet of rubber or other suitable material 13.

The front or cover plate 12 corresponds in 70 width to the width of the front face 10 of the head, and the sheet or plate 13, of rubber or the like, is of less width, so that a longitudinally-extending discharge opening or space 14 is formed between the lower edges of the 75 plate 12 and the head 8, as clearly shown in Figs. 3 and 5 of the drawings. By using sheets or plates 13 of different thicknesses, so that the cover-plate 12 will be spaced at a greater or less distance from the face 10 of the head 8, it will be seen that the discharge-opening 14 in the latter may be varied as desired or according to the character of the carpet or other material to be cleaned. The plates 12 13 may be removably secured in the 80 recess 11 in the face 10 by screws or similar fastening means 15.

The nozzles 7 are pivotally mounted by providing in their ends tubular trunnions or shafts 16, which extend through bearing-openings formed in the ends of the box or casing 2 and have upon their outer ends tapered plugs 17. The latter are seated in tapered openings 18, formed transversely in air pipes or tubes 19, provided at the ends of 95 the device. The plugs 17, which turn with the shaft 16 and the nozzles 7, have openings 20, which register with the longitudinal openings or bores in the device 19 and are retained in the transverse openings 18 by 100 washers and screws 21.

To cause the nozzles 7 to swing simultaneously, I secure upon their shaft 16, by means of set-screws 22, segmental gears 23, which mesh with each other, as clearly shown in the drawings. The nozzles may be secured in an adjusted position in any suitable manner; but I preferably employ a set-screw 24 in one of the gears 23 to accomplish this result. This set-screw 24 is adapted to impinge 110

against the outer face of the end of the box or casing 2, so as to firmly secure the two nozzles against movement.

The pipes 19 have their forward ends closed and their rear ends screwed into inwardly-extending elbows 26, which have in their inner ends pipe-sections 27, in which are provided unions 28. The pipe-sections 27 are screwed into the opposing branches of a T-coupling 29, which has formed integrally with it an attaching-bracket 30. The latter is secured by screws or other suitable fastenings upon the rear side of the box or casing 2, and connected to the third branch of the T-coupling 29 is an air-supply pipe 31, which consists of short pipe-sections, elbows, and a controlling-valve 32, which may be of any desired form and construction. A flexible pipe leading from an air-pump, a tank of compressed air, or any other suitable source of supply for the air or other gas used for cleaning purposes is adapted to be coupled to the upper end of the pipe 31, as will be readily understood.

Surrounding the nozzles 7, within the box or casing 2, is a receptacle 34. This receptacle, which is preferably formed of sheet metal, is of substantially the same shape as the interior of the box 2 and consists of a surrounding side wall 35, which is spaced from the side wall of the box, a bottom 36, which is spaced, as shown at 37, from the bottom 5 of the box, and a rectangular portion 38, which incloses the two nozzles 7. By thus forming the receptacle and spacing it from the box or casing 2 it will be seen that the dust and dirt loosened by the two opposing blasts of air from the nozzles 7 will pass upwardly through the space between the box and receptacle and over the upper edge of the latter and into it and the open upper portion of said box. A surrounding shield or deflector 39 is preferably provided in the upper portion of the box 2 above the upper edge of the side wall 35 of the receptacle. This deflector, as shown, is in the form of an angle metal strip, which is seated upon the upper edge of the box and has an inwardly-projecting portion 40 to deflect the dust downwardly into the said receptacle.

In order to strain the air passing into the box or casing and to permit it to discharge from the same, I preferably provide upon the box 2 a bag or sack 41, of canvas or other suitable fabric, which serves as a strainer. This bag 41 has its open end secured beneath the flanged top or upper edge 3 of the box 2 by means of a surrounding clamping-band 42, which may be of rubber, metal, or any other suitable material. The bag 41 is adapted to be supported above the box 2 by a hanger 43, which is preferably in the form of a rod having its lower end detachably and adjustably secured by means of set-screws 44 in sockets 45, provided upon the rear side

of the box 2 and at its upper end any suitable means for supporting the bag. As shown, this means consists of providing the upper end of the hanger-rod 43 with a hook adapted to be engaged by a loop or eye provided upon the bag.

To permit the box 2 to be conveniently moved over the carpet or other surface to be cleaned, I provide a handle 46. The latter has a hand-grip 47 at its outer end and a forked or bifurcated portion 48 at its inner end. The arms or ends of this forked portion of the handle are pivoted, as at 49, upon the centers of the ends of the box 2, and they have a slight longitudinal curvature, as shown.

The construction, use, and advantages of the invention will be readily understood from the foregoing description, taken in connection with the accompanying drawings.

It will be seen that when the valve 32 is open to permit air to be forced through the supply-pipes and out of the discharge-openings 14 in the nozzles 7 the blasts discharged therefrom will be directed toward or across each other, so that they meet at the bottom of the nap of the carpet or other material being cleaned, and thereby effectively loosen and remove the dust therein. By adjusting the nozzles angularly with respect to each other it will be seen that these opposing blasts of air may be caused to meet at different points beneath the bottom 5 of the box or casing, according to the length of the nap of the carpet or other material to be cleaned.

It will also be noted that by varying the thicknesses of the rubber sheets 13 beneath the cover-plate 12 of the nozzle the amount of air discharged therefrom may be regulated according to the character of the carpet or other surface to be cleaned.

Various changes in the form, proportion, and the minor details of construction may be resorted to without departing from the principle or sacrificing any of the advantages of this invention as defined by the appended claims.

Having thus described my invention, what I claim as new, and desire to secure by Letters Patent, is—

1. A machine of the character described and comprising a dust-receiver having an opening in its lower side, pivotally-mounted discharge-nozzles in said receiver above said opening for discharging air under compression through said opening and means to adjust said nozzles angularly with reference to each other.

2. In a machine of the character described, comprising a dust-receiver having an opening in its lower side, a pair of pivotally-mounted discharge-nozzles in said receiver above and discharging into said opening, gears connecting said discharge-nozzles together for simultaneous movement in re-

verse directions to dispose said nozzles at any desired angular adjustment with reference to each other, and means to secure said nozzles when thus adjusted.

5. 3. A device of the character described comprising a dust-receiver having an opening in its bottom, discharge-nozzles arranged above said opening, tubular trunnions upon said nozzles for pivotally mounting them in said receiver, and having tubular plugs at their outer ends, a supply-pipe having seats to receive said plugs, and means for adjusting said nozzles angularly with respect to each other.

15. 4. A device of the character described comprising a dust-receiver having an opening in its bottom, discharge-nozzles arranged

above said opening, tubular trunnions upon said nozzles for pivotally mounting them in said receiver, and having tubular plugs at their outer ends, pipes having seats to receive said plugs, meshing-gears upon said tubular trunnions, a set-screw for holding said nozzles in an adjusted angular position, an air-supply pipe connected to said pipes, and a valve for controlling the supply of air.

In testimony whereof I have hereunto set my hand in presence of two subscribing witnesses:

ROBERT H. DUESING.
